UNITED STATES PATENT OFFICE.

RALPH G. SHELDEN, OF ANN ARBOR, MICHIGAN.

COIN-RELEASED CHAIR OR SEAT.

1,182,108.

Specification of Letters Patent.

Patented May 9, 1916.

Application filed July 17, 1914. Serial No. 851,623.

To all whom it may concern:

Be it known that I, RALPH G. SHELDEN, a citizen of the United States, residing at Ann Arbor, in the county of Washtenaw and 5 State of Michigan, have invented certain new and useful Improvements in Coin-Released Chairs or Seats, of which the following is a specification.

My invention relates to coin freed folding 10 chairs, and has for its object to provide certain improvements in the construction and operation of the same, as will be hereinafter more definitely pointed out.

The chair or seat is in appearance, similar 15 to an ordinary folding theater chair or seat with a boxed-in inclosure extending down the center of the back, which contains the working parts of the device. The normal position of the chair or seat is raised, but 20 upon dropping a coin of a certain size into a slot and slightly moving a lever the seat drops to nearly the correct position for use. By pressure, either by sitting or by the hand, the seat is forced farther down to the correct 25 position for use. The lowering of the seat to the correct position for use moves certain other parts hereinafter described so that as soon as the party rises from the seat a weight or spring will immediately raise it to the 30 original normal position.

The mechanism for operating the chair or seat is illustrated in the accompanying drawings, in which:—

Figure 1 is a rear elevation of my improved device. Fig. 2 is a side elevation of the same. Fig. 3 is an enlarged detail view similar to Fig. 2 of the pivot of the seat and its locking and operating mechanism. Fig. 4 is an enlarged sectional view of the same 35 parts looking in the same direction. Fig. 5 is a detail perspective view of the lower end of the seat and its locking parts.

Similar letters and figures denote corresponding parts in the several views.

In the said drawings, the reference numeral F denotes a suitable frame, which encloses the working parts, and supports the chair back B and the seat S, the latter being pivoted on the pin P in said frame. Also 45 pivoted at 1' in said frame is a lever 1 curved at its lower end and adapted when the seat S is in the raised position to engage a shoulder or abutment 12, formed at the lower end of the extension S' of the seat S. A carriage 2, formed of two members connected by cross pins 13 and 14 and disposed upon

opposite sides of a vertical guide 11 supported by the frame F and provided with a curved slot G, has said members toothed at 15 in their front faces to engage another 60 shoulder or abutment 16, formed at the lower end of the extension S'. The pin 14 connecting the members of the carriage 2 is of a size approximately to fit the slot G in plate 11, while the pin 13 is somewhat smaller, 65 whereby a slight rocking movement of the carriage 2 is permitted on the pin 14 as a fulcrum. Projecting from one side of one of the members of the carriage 2 is a horizontally disposed pin 17, which lies in the 70 path of movement of the lower end of the lever 1, as shown in Fig. 5.

Pivoted to the extension S' at one side is a rod 7, extending downwardly and toothed at 7' to engage a segmental pinion 8, which is 75 in turn fastened to a larger pinion 9, so that the two move together. Said pinion 9 is in mesh with a rack 10' on the lower end of a rod 10 that at its upper end is pivoted to one of the members of the carriage 2. Also 80 pivoted to the lower end of said carriage at 18 is a rod 19, which carries at its lower end a suitable weight W.

The lever 1 extends upwardly above and in proximity to the grooved plate 4, which is 85 in alinement with the coin receiving tube 3, while pivoted at 6' is a lever or shaft 6 that at its lower end is in alinement with the upper end of the lever 1, and at its upper end is engaged by the lower end of a lever 5 pivoted at 5' and projecting at its upper end through a slot in the frame F, said upper end being provided with a suitable hand hold.

In operation, the introduction of a coin 95 into the coin tube 3 causes said coin to be guided to the plate 4 where it will interpose between the lower end of the lever 6 and the upper end of the lever 1, thereby forming a connection between the two. Now, upon a further pull on the lever 5, which will be imparted to the lever 6, the lower end of the latter will be moved forward, and, through the coin, will correspondingly move the upper end of the lever 1, and at the same time will move the coin along the groove in said plate 4 until a hole in the plate is reached through which the coin will drop into a collecting receptacle R. This movement of the coin will move the lower end of the lever 100 rearwardly disengaging said lower end from the shoulder or abutment 12 on the exten-

sion S', and said movement will at the same time, through the engagement of the back of said lever 1 with the pin 17 on the carriage 2 rock the latter upon the pin 14 as a pivot 5 until the smaller pin 13 thereof strikes the back of the slot G in plate F, which movement is sufficient to disengage the teeth 15 of the carriage 2 from the shoulder or abutment 16 of the extension S'. This results in 10 a release of said extension S', and the weight of the seat S will cause the seat to drop approximately two-thirds of the distance toward the open position, this movement being limited by the engagement of the rack 7 on 15 rod 7 with the toothed segment 8, said rod 7 being raised with the extension S' as the seat drops. Upon pressure now being applied to the seat S, either by the hand of the occupant or by his occupying the seat, the latter is forced to its lowermost horizontal position, which results in a further lift of the extension S' and with it the rod 7, which in 20 turn rotates the segments 8 and with it the segment 9. The latter by its engagement with the rack 10' raises the latter and its lever 10, which being attached at its upper end to the carriage 2 raises the latter, the same following the slot G in the plate F, and, by reason of the weight W attached at 25 18 to its front lower end, tilting said carriage so that the cross pin 13 thereof can bear against the front of said slot G. This movement of the rod 10 and the carriage 2 is sufficient to cause the teeth 15 of the latter to pass the shoulder or abutment 16 30 on the extension S', as shown in dotted lines in Fig. 3, said teeth 15 riding past said shoulder and interlocking over the top of the same, in a manner readily to be understood. This places the parts in such position that upon pressure being relieved from the seat S, by the rising of the occupant, the weight W through the carriage 2 upon which it pulls will exert a pull upon the extension S' of the seat S, which will cause 35 the latter to immediately resume its vertical or closed position, shown in Figs. 1 and 2. In this movement of the seat S to closed position, the extension S' will ride past the lower end of the lever 1, so that the latter will again assume its initial position in contact with the shoulder or abutment 12 and its extension S', as shown in Figs. 3, 4 and 5.

Having thus described my invention, what 50 I claim as new and desire to secure by Letters Patent, is:—

1. The combination with a chair frame, and a seat pivoted therein, of means engaging said seat normally to retain the same in 55 folded position, coin operated means for releasing said seat and permitting a movement

thereof by gravity toward the open position, and retracting means brought into operation by the further movement of the seat to its open position, and adapted when said seat is 60 released to raise it to closed position.

2. The combination with a chair frame, and a seat pivoted therein and provided with an end extending beyond its pivot, of means engaging said end normally to retain the 70 seat in folded position, coin operated means for releasing said end and permitting a movement of the seat by gravity toward the open position, and retracting means brought into operation by the further movement of 75 the seat to its open position, and adapted when said seat is released to return it to the closed position.

3. The combination with a chair frame, and a seat pivoted therein and provided with 80 an end extending beyond its pivot, of a lever engaging said end normally to retain the seat in folded position, coin operated means whereby said lever may be moved to release said end and permit a movement of the seat 85 by gravity toward the open position, a rod carried and moved by said end, and mechanism operated by said rod as said seat is moved to its open position to engage the seat end and return it and the seat to folded position 90 when said seat is released.

4. The combination with a chair frame, and a seat pivoted therein and provided with an end extending beyond its pivot, of a locking lever engaging said end, a movable 95 carriage, a slotted plate controlling the movement of said carriage, a weight carried by said carriage and adapted to rock the latter to lock with the end of the seat, whereby upon the release of the seat the same will 100 be returned to its folded position.

5. The combination with a chair frame, and a seat pivoted therein and provided with an end extending beyond its pivot, a rod carried by said end and movable therewith, a 105 rack on said rod, a small segmental pinion adapted to be engaged by said rack, a large segmental pinion fixed to said small pinion, a lifting rod having a rack engaged by said large pinion, a carriage to which said lifting 110 rod is pivoted, means for guiding said carriage in a predetermined path, whereby it will when lifted engage with the end of said chair seat, and a weight pivoted to said carriage and adapted when said chair seat is 115 released to move said carriage and seat, whereby the latter will assume its folded position.
